(57) **CLAIM**

The ornamental design for a medical immunoassay device, as shown and described.

DESCRIPTION

FIG. 1 is a top, front and side perspective view of a medical immunoassay device showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a top, front and side perspective view thereof, with a cover in an opened position.

The broken lines are included for the purpose of illustrating portions of the medical immunoassay device that form no part of the claimed design.
